(57) **CLAIM**

The ornamental design for a vehicle rack, as shown and described.

DESCRIPTION

FIG. 1 is a perspective view of a vehicle rack mounted to an exemplary vehicle showing our new design.

FIG. 2 is a perspective view of a vehicle rack.

FIG. 3 is a front elevational view of FIG. 2.

FIG. 4 is a top elevational view of FIG. 2.

FIG. 5 is a side elevational view of FIG. 2.

FIG. 6 is a bottom elevational view of FIG. 2.

FIG. 7 is an additional side elevational view of FIG. 2; and, FIG. 8 is a rear elevational view of FIG. 2.

In the drawings, the broken lines depict portions of the article that form no part of the claimed design.
